UNITED STATES PATENT OFFICE.

HARRY MERCER, OF BIRMINGHAM, ALABAMA.

DESIGN FOR A SPOON.

SPECIFICATION forming part of Design No. 21,144, dated November 3, 1891.

Application filed September 21, 1891. Serial No. 406,406. Term of patent 7 years.

To all whom it may concern:

Be it known that I, HARRY MERCER, a citizen of the United States, residing at Birmingham, in the county of Jefferson and State of Alabama, have invented and produced a new and original Design for Spoons; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

The single view of the drawing is a plan of a spoon of the novel design, the one view being deemed sufficient to illustrate the invention.

The leading feature of the design consists in the spoon-handle resembling in plan a smoke pipe or stack, and in the peculiar ornamentation on the bowl representing a smelting-furnace.

In said drawing, *a* indicates the concave bowl of a spoon, and *b* the handle thereof.

The said handle has a shape, when viewed in plan, in resemblance to a smoke-stack *c c*, having the shape of sheet-metal plates *d d*, and rivet-shaped heads in series parallel with lines *e* having the appearance of joints. The extremity of the handle is of an ornamental shape resembling that of a chimney or stack, as at *f*.

The bowl of the spoon on the concaved side is ornamented with a figure or group of figures representing or shaped like the buildings of a smelting or blast furnace, *g* indicating the stack, *h h* two stoves, *i* furnace and top, *j* the east-house, and *k* a track-terminal.

What I claim as new is—

The design for a spoon herein shown and described.

In testimony that I claim the foregoing I have hereunto set my hand this 12th day of September, 1891.

HARRY MERCER.
